(57) CLAIM

The ornamental design for a multimedia desk, as shown and described.

DESCRIPTION

FIG. 1 is a front perspective view of a first embodiment of a multimedia desk showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view of a second embodiment of my design which differs from the first embodiment only in that the display screens of the second embodiment have been retracted to a hide position within the interior of the desk.
